US00D991960S

(12) **United States Design Patent** (10) **Patent No.:** **US D991,960 S**
Stipech et al. (45) **Date of Patent:** **** Jul. 11, 2023**

(54) **DISPLAY SCREEN OR PORTION THEREOF WITH GRAPHICAL USER INTERFACE**

(71) Applicant: **Block, Inc.**, San Francisco, CA (US)

(72) Inventors: **Kristopher David Stipech**, West Hollywood, CA (US); **Robert Andersen**, New York, NY (US); **Jordan Singer**, New York, NY (US)

(73) Assignee: **Block, Inc.**, Oakland, CA (US)

(**) Term: **15 Years**

(21) Appl. No.: **29/866,971**

(22) Filed: **Oct. 3, 2022**

Related U.S. Application Data

(60) Continuation of application No. 29/826,974, filed on Feb. 16, 2022, now Pat. No. Des. 969,850, which is a continuation of application No. 29/765,055, filed on Jan. 5, 2021, which is a division of application No. 29/696,654, filed on Jun. 28, 2019, now Pat. No. Des. 916,917.

CLAIM

The ornamental design for a display screen or portion thereof with graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof with graphical user interface.

The dashed broken lines depict a device, portions of the display screen, and portions of the graphical user interface that form no part of the claimed design.
